FURNITURE SEAT

Burton H. Kaplan, Potomac, Md., assignor to
Rowe Furniture Corporation

Filed June 9, 1975, Ser. No. 584,724

Term of patent 14 years

Int. Cl. D6—01

U.S. Cl. D6—63

FIG. 1

FIG. 2

FIG. 3

FIG. 1 is a front perspective view of a furniture seat in the form of a davenport;

FIG. 2 is a side elevation of a furniture seat illustrated in FIG. 1; and

FIG. 3 is a front perspective view of a furniture seat illustrated in FIG. 1, shown in the form of a love seat.

The back of a furniture seat is plain and conventional throughout, and the sides of the davenport and love seat not shown are identical to those which are shown.

The design is characterized by the particular trim strip extending along the forward edges of the base and armrest members of the specifically configured sofa, with the strip being wide throughout and upwardly tapered along the armrest members, all as best illustrated in FIG. 1.

I claim:

The ornamental design for a furniture seat, substantially as shown and described.
